US00D918215S

(12) **United States Design Patent** (10) **Patent No.:** **US D918,215 S**
(45) **Date of Patent:** **** May 4, 2021**

(54) **CASE FOR TABLET COMPUTER**

(71) Applicant: **SPIGEN KOREA CO., LTD.**, Seoul (KR)

(72) Inventor: **Young Kwang Hyun**, Seoul (KR)

(73) Assignee: **SPIGEN KOREA CO., LTD.**, Seoul (KR)

(**) Term: **15 Years**

(21) Appl. No.: **29/726,159**

(22) Filed: **Feb. 28, 2020**

(51) LOC (13) Cl. **14-02**

(52) U.S. Cl.

USPC **D14/440**

CLAIM

The ornamental design for a case for tablet computer, as shown and described.

DESCRIPTION

FIG. 1 is a front perspective view of a case for tablet computer showing my new design;

FIG. 2 is a rear perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

1 Claim, 8 Drawing Sheets
